CASING FOR A FLUID CONDUIT COMPONENT

Jorgen Hogh and Adam Bonne, Copenhagen, Denmark,
assignors to A/S Teknova, Niva, Denmark

Filed June 21, 1973, Ser. No. 372,344

Claims priority, application Denmark Dec. 28, 1972

Term of patent 14 years

Int. Cl. D23—01

U.S. Cl. D23—19

FIG. 1

FIG. 2

FIG. 3

FIG. 4

FIG. 5

FIG. 1 is a perspective view of a casing for a fluid conduit component showing our new design;

FIG. 2 is a side elevational view thereof the opposite side being the same as the side shown;

FIG. 3 is an end elevational view thereof, the opposite end being the same as the end shown;

FIG. 4 is a top plan view thereof; and
FIG. 5 is a bottom plan view thereof.

We claim:

The ornamental design for a casing for a fluid conduit component, as shown and described.
